ZONED EVAPORATOR MAT FOR AIR COOLERS

Archie S. Feinberg, Dallas, Tex.

Application November 5, 1947, Serial No. 784,181

4 Claims. (Cl. 261—28)

1

This invention relates to air coolers of the evaporative type and it has more particular reference to improvements in such devices calculated to render them effective in regions where they are not practical as now generally constructed.

The principal object of the invention is to widen the territorial scope of usage of the evaporative type of coolers by reducing the dampness associated with their functioning under various climatic conditions and thus make feasible their successful operation in regions where their use is now considered unsatisfactory and also, to improve the performance of the evaporative cooler in those hotter and more arid regions, during certain periods, where it is now in wide and successful use.

Another object of the invention is to provide an apparatus and method providing "zoned" evaporation to eliminate objectionable characteristics of evaporative coolers in more temperate, semi-humid regions, and to make feasible evaporative cooler use in such regions by attuning its vaporization to the balanced atmospheric laws of nature which affect moisture evaporation out-of-doors, and the inverse temperature and humidity action which attends such evaporation. By permitting only prejudged and varying amounts of heat transfer vaporization under variable outdoor temperature, moisture vapor and latent heat conditions, definite protection against over-humidification indoors without sacrifice of cooling comfort is afforded.

Broadly, the invention seeks to adapt the evaporative type cooler to wider use by providing a cabinet in which the filter mat or mats of wood fibers or the equivalent is wetted in restricted areas, herein referred to as "zones," the extent of the restricted areas to be wetted being determined by temperature variations which cause, through thermostatic means, the actuation of baffles to increase or decrease the degree of saturation of the mat.

To explain the manner in which these improvements apply, it is first necessary to review the mode of functioning of the conventional evaporative cooler, its advantages and shortcomings and particularly, the importance of territorial and climatic application to its operation.

Water alone is the temperature reducing medium of the evaporative cooler. It employs no ice or refrigeration chemical. The success or failure of its operation depends upon the quantity of moisture it is able to evaporate without causing too high a relative humidity in the air it condi-

tions. Thus, its performance is directly related to, and controlled by, the type of climate in which it functions. The prevailing dry bulb (Fahrenheit) thermometer temperature, the wet bulb temperature, the relative humidity that exists and the ability of the air to absorb moisture are the determining factors of its effectiveness as a comfort creating agent. Because of the ability of air to approximately double its water vapor carrying capacity with every 20° increase in temperature, the evaporative cooler functions best in those areas where the temperatures are the highest and the air the driest, and functioning without dampness objections. (Air at 80° Fahrenheit contains 10.9 grains of moisture per cubic foot when totally saturated whereas its total saturation capacity at 100° is 19.7 grains.)

The evaporative cooler extracts no heat from the air. Its function is one of heat transfer wherein the temperature reduction which registers on a thermometer during its operation is due to change in the form of the heat the air contains. In explanation, heat is necessary to evaporation and in this instance, a portion of the air's sensible heat supports the vaporization occurring within the cooler. This vaporization converts such sensible heat as is used in the process into latent heat, i. e., latent heat of vaporization. Because sensible heat alone registers on an ordinary Fahrenheit dry bulb thermometer, the sum total of the sensible heat so converted thus appears on the thermometer as a reduction in temperature. The wet bulb thermometer, which registers the sum total of the air heat content, both sensible and latent, is not lowered during the process. Sensible heat loss must inevitably result in equivalent latent heat gain and this forms much of the basis for the high humidity, dampness complaints associated with evaporative cooler functioning.

The evaporative cooler, unlike refrigeration, cannot remove moisture from air. Instead, moisture absorbed by the air passing through the moistened pads or spray of the cooler adds to the air's humidity and this, coupled with a reduced dry bulb temperature, the wet bulb remaining stationary, accounts for considerable increase in both relative humidity and latent heat in the conditioned air. Dampness resulting from such functioning greatly restricts its use to hot, dry sections of the country where it is not stigmatized as "wet" air conditioning. Its performance in these arid regions is insured against dampness by the hot temperatures which exist. For example, a typical day of 106° F. with a wet bulb

of 68° will result with a conventional cooler in a conditioned air temperature of 77½° Fahrenheit (dry bulb), a wet bulb temperature of 68° and a not perceptibly high relative humidity of 61½%.

(The foregoing calculations are made on the basis of customary evaporative cooler functioning of 75 percent "cooling of the wet bulb depression" efficiency.) ("Wet bulb depression" is a term used in the air conditioning industry to denote difference in degrees between the air's dry bulb and wet bulb temperatures.)

In the semi-humid, more temperate northern, northeastern and/or upper Mississippi River Valley regions of the United States, a less ideal, different conditions exists, which affect evaporative cooler functioning. Temperatures are lower and humidities are higher. The air cannot carry as much moisture at these lower temperatures; thus, its use in these areas on other than abnormally hot days results in atmospheres too high in humidity with resultant dampness menacing to merchandise, furniture, fixtures, etc.

With the foregoing objects in view, the invention has further reference to certain features of accomplishment which will become apparent as the description proceeds, taken in connection with the accompanying drawings wherein:

Figure 1 is a side elevational view of an evaporative cooling unit constructed according to the present invention shown as being installed on a building roof with provisions for thermostatic control out of the influence of reflected heat.

Figure 2 is a view on a larger scale showing the evaporative cooling unit in vertical section.

Figure 3 is a view in transverse section, taken on line 3-3 of Figure 2.

Figure 4 is a fragmentary perspective view of a baffle assembly showing the operating means therefor, and

Figure 5 is a suggested wiring diagram.

Continuing with a more detailed description of the drawing, reference numeral 10 denotes a cabinet which is arranged in a manner best suited to the air intake of an enclosure or building to be cooled, usually on the top of the building, as exemplified in Figure 1 in which 11 indicates the roof and 12, the cornice of the building.

Within the front portion of the cabinet 10 is arranged a blower casing 13 containing a blower 14 which is driven by a motor 15 through the medium of a belt 16. Within the rear portion of the cabinet 10 is mounted a filter mat 17 of fibrous material, such as wood shavings, which is preferably partitioned into vertical sections A, B and C (Fig. 3) which are herein referred to as "zones."

At the approximate midsection of the mat 17 or zone A is mounted a disc 18, known as a "hydro-spray" and this disc is rotated rapidly by a small motor 19 mounted on the opposite side of the mat 17. A water pump 20 is submerged in the water of a basin 21 in the bottom of the cabinet and functions to convey water through a line 22 and project the same onto the face of the hydro-spray 19. Water impinging the disc 18 is radially discharged thereby in a sheet spray which latter is influenced in the direction of the mat 17 by the suction of the blower 14.

The elements described in the foregoing are not herein considered new, these being present in the conventional evaporative cooler. However, as far as is known, there is no provision made in the conventional cooler for wetting predetermined areas of the mat to vary the amount

of moisture to be entrained in or absorbed by the air passing through the mat in accordance with varying outside temperatures.

To accomplish this, the invention provides an assembly of vertical, overlapping baffles 23 which are adapted, in closed position, to isolate the zone B from the zone A and similarly, a second assembly of baffles 24 which isolate the zone C from zone A. Actually, these baffles restrict the water discharge of the hydro-spray 18 by closing off one or both of the zones B or C in the manner to be presently described when outside temperatures require. The central section of the mat or zone A is always exposed to the discharge of the spray 18 since it would be seldom if at any time the unit is operated without moisture. To insure against capillary attraction tending to influence moisture from one to another of the mat zones, a separator or partition 25 is interposed between the sections defined as zones.

The baffles 23 are identical to baffles 24 and each consists of an elongated, vertical plate pivoted at a and b at its top and bottom respectively (Fig. 2). To the upper pivot a of each baffle plate is connected the end of an arm 26 and the opposite ends of these arms are pivoted to a link 27. At the midsection of this link is a pair of ears 28 (Fig. 4) and to these ears is connected a slotted crank 29, the latter being mounted on the armature shaft 30 of a small motor, mounted in a housing 31. The motor for operating baffles is of conventional manufacture, is geared to slow speed and its shaft 30 oscillates through an arc of approximately 90° to open and close the baffles 23 or 24.

The baffles 23 and 24 are each provided with an offset lip 32 along one edge which is adapted to overlap the edge of an adjacent baffle to afford a positive seal against passage of water therebetween.

When an evaporative cooler is mounted on the roof of a building the reflected heat adjacent the unit is usually of a temperature much in excess of the mean atmospheric temperature. Accordingly, in order that the zones C and B may function in keeping with variations in actual atmospheric temperature, thermostats 33 and 34 are suspended over the side of the building and are preset to operate the motors which actuate the baffles 23 and 24 respectively. This is borne out in the wiring diagram disclosed in Figure 5.

It is at once apparent that at comparatively low temperatures and during periods of relatively high humidity, it is desirable in the interest of comfort to reduce the saturated area of the mat 17 to the minimum of one zone, i. e., zone A. As the temperature rises, the thermostat 33, preset to close the circuit to the motor which actuates the baffle assembly 23, functions to open these baffles, and exposes zone B to the discharge of the hydro-spray 18. At still higher temperatures, thermostat 34 will be actuated to close the circuit to the motor which operates the baffle assembly 24, thereby exposing zone C to the discharge of spray 18. Thus the maximum area of the mat 17 become saturated.

It is obvious that when only zone A, or zones A and B, are wetted, the reduction in vaporization will not depress the Fahrenheit thermometer temperature to as low a degree as when full evaporation is permitted. This does not appreciably affect interior comfort, being compensated for by the greater moisture deficiency of the conditioned air. A higher rate of evaporation and body heat loss from skins of room occupants results in "effective temperatures" but little at variance with

those under the more humid atmospheres produced by full evaporation. ("Effective temperatures," as charted in the American Society of Heating and Ventilating Engineers guide reflect the cumulative comfort quality of temperature, humidity and air motion taken together, which influence the transference of body heat and determine the feeling of warmth. Such research has shown that dry air at a relatively high temperature may feel cooler than air of considerably lower temperature with a high moisture content.)

When outdoor temperatures reach 92 degrees Fahrenheit and over, with full evaporation from all zones functioning, moisture saturation capacity of the air at these temperatures in such as to afford protection against dampness thru over-humidification when passed thru the evaporative cooler. Unnecessary on these hotter days, zoned evaporation is needed during the great majority of more temperate summer season days which prevail in these regions, when, without sacrifice of comfort cooling results, protection against dampness is desired.

Manifestly, the construction as shown and described is capable of some modification and such modification as may be construed to fall within the scope and meaning of the appended claims is also considered to be within the spirit and intent of the invention.

What is claimed is:

1. An evaporative cooling apparatus including a cabinet having an open rear, a blower in said cabinet provided with an air inlet and an air discharge opening at the front of said cabinet, a filter mat divided into a plurality of independent sections through which air is drawn by said blower, a water spraying device adapted to saturate the entire area of said filter mat, a plurality of groups of vertically disposed baffles in the rear of said cabinet for isolating pre-selected areas of said mat into separate zones, said groups of baffles each comprising a series of plates pivoted for common movement to a position to shield a preselected area of said mat against saturation by said spraying device, and thermostatically actuated means for moving the plates of said groups of baffles to expose said zones to the saturating action of said spray in accordance with variations in atmospheric temperature.

2. In an evaporative cooler, a cabinet having a blower therein provided with an air inlet and an air outlet for discharging air at the front of said cabinet, a filter mat for said air inlet through

which air is influenced by said blower, means disposed centrally of said mat for spraying water against the entire area of said mat, a plurality of groups of baffles adjacent said mat, each group comprising a series of vertically disposed plates pivoted for common movement to a position to shield a predetermined portion of said mat area from the product of said water spraying means, and thermostatically controlled means for effecting common pivotal displacement of the baffles of each group to increase and decrease that portion of said mat exposed to said water spraying means in accordance with variations in atmospheric temperature.

3. In an evaporative cooler, a filter mat in vertical, horizontally aligned sections, a blower for influencing air through said mat sections and for discharging the air drawn thereby, means for wetting all of said mat sections simultaneously, a series of groups of baffles disposed adjacent said filter mat, each of said groups comprising a series of plates pivoted for common movement effective to positively open and close said mat sections to said wetting means and thermostatically actuated means for operating said baffles upon changes in atmospheric temperature.

4. In an evaporative cooler, a filter mat divided into a plurality of separate sections in the same plane, blower means for drawing air through said filter mat, a water spraying means capable of saturating all of said mat sections simultaneously, a series of pivoted baffles adapted to be closed to intercept the water of said spraying means which would normally fall upon the outer of said mat sections but effective to permit continued flow of air through said outer mat sections under the influence of said blower means, and thermostatically operated means for actuating said baffles in accordance with variations in atmospheric temperatures.
